UNITED STATES PATENT OFFICE.

ROBERT L. FARGO, OF LOS ANGELES, CALIFORNIA.

SUPPORTING DEVICE FOR CIGAR HOLDERS, CIGARETTE HOLDERS, AND OTHER ARTICLES.

Application filed November 30, 1923. Serial No. 677,690.

To all whom it may concern:

Be it known that I, ROBERT L. FARGO, a citizen of the United States, and a resident of Los Angeles, county of Los Angeles, and 5 State of California, have invented certain new and useful Improvements in Supporting Devices for Cigar Holders, Cigarette Holders, and Other Articles, of which the following is a specification.

10 In the use of cigar holders, cigarette holders, pipes, fountain pens and other articles, it is often necessary to place them upon a table or other support and at the same time it is not desirable to have the 15 ashes of the cigar or cigarette, or the ink of the fountain pen come in contact with the support or contiguous articles, and while devices have been provided on which such articles may be placed, such devices are not 20 always at hand and they are more or less cumbersome and inconvenient.

It is an object of my invention to provide a supporting device of such construction that it can be conveniently carried by and 25 as a part of the article itself so that it shall be always available for use.

Again I aim to provide a device of this character which can be quickly and easily attached to pipe holders, cigarette holders, 30 fountain pens and other articles.

It is also an object of my invention to provide a supporting device which shall also serve to ornament the article to which it is attached or with which it is associated.

35 My invention consists generally in a device of the form, arrangement, construction and the co-operation of the parts, whereby the above named objects, together with others that will appear hereinafter, are attainable, and my invention will be more 40 readily understood by reference to the accompanying drawings which illustrate what I consider, at the present time, to be the preferred embodiment thereof.

45 In said drawings:

Fig. 1 is a side view of a cigarette holder construction embodying my invention.

Fig. 2 is a view substantially on the line 2-2 of Fig. 1, but illustrating the supporting device in the course of being swung to inoperative position.

50 Fig. 3 is a perspective view of the supporting device shown in Figs. 1 and 2 and detached from the holder which it is designed to support.

Fig. 4 is a view similar to Fig. 1 but illustrating a modified form of my invention.

Fig. 5 is a perspective view of the supporting device of Fig. 4 detached from the holder.

Fig. 6 is a view of the pipe equipped with a supporting device embodying my invention.

Fig. 7 is a fragmentary view of a pipe provided with a modified supporting device embodying my invention; and

Fig. 8 is a detail bottom view of a slightly different supporting device embodying my invention.

In the drawings I have shown as articles 70 to be supported, cigarette holders and pipes, but I wish it to be understood that my invention is applicable to fountain pens, pencils and other articles, so that the illustrated articles should be taken as by way of illustration and not by way of limitation.

Referring first to the constructions shown in Figs. 1 to 3, 1 represents a cigarette holder which may be of any desired construction, but which, as here shown, is provided with 80 a cigarette holding end portion 2 of cylindrical or circular cross section and which contains a central opening 3 for the reception of the cigarette 4 which is indicated by means of dotted lines in Fig. 1. 5 represents the table or other surface upon which the cigarette holder is to be supported in such manner that the cigarette will be elevated therefrom. To this end I have provided a supporting device which, as here shown, 85 is composed of a band 6 of such size that it may be slipped on to the portion 2 from the small end, the portion 2 tapering slightly, and moved to the left until it is firmly held thereon by frictional engagement, although 90 if desired the band may be permanently secured to the holder. However, the separate band has some advantages as the supporting device may be quickly and easily associated 95 with holders of various kinds. Pivots 7 and 8 are secured to the band 6 at diametrically opposite points, as by means of the pivots 7 and 8 will be found strut-like members or parallel arms 9 and 10 which, as here shown, are connected by means of the curved portion 11 arranged at substantially a right angle thereto. This portion 11 is shaped to conform generally to the curvature of that portion of the holder with which it is designed 100 to be associated. As a matter of fact, I

prefer to make the curvature of the portion 11 such that the distance between the opposite points 12 and 13 thereof will be slightly less than the external diameter of the holder at that point. This is well shown in Fig. 2 wherein it will be observed that in order to swing the supporting device into its final inoperative position, being the position shown by means of dotted lines in Fig. 1, it will be necessary to spring the portions 12 and 13 slightly outwardly until the center line of the holder is passed and these portions will then snap into place and serve effectually to hold the support against undesired movement. At the same time, when it is to be used, the support can be very readily moved to the full line position shown in Fig. 1. The supporting device will preferably be made of light gauge metal and may be of gold, silver or other metals of a non-corrosive nature and which will be of pleasing appearance. The supporting device serves as an ornamentation for the holder, as well as the utilitarian purpose of supporting it.

In order to prevent the struts or arms 9 and 10 from being swung beyond their desired operative or supporting position, I provide a stop, which as here shown, is in the nature of a projecting portion 14 on each side of the band 6 with which the squared end portion 15 of the struts 9 and 10 engages.

In Figs. 4 and 5 I have illustrated a slightly modified form of my invention. In this instance the holder 16 is of slightly different form but is provided with an end portion 17 of circular cross-section and which is provided with an internal opening to receive the cigarette 18 shown by means of dotted lines. The holder 16 is supported above the table 19 by a supporting device comprising a band 20 which is frictionally held in place on the holder portion 17. On the band portion 20 will be found a plurality of studs 21 to which there is swingably secured, by means of the pivot 22, a strut 23, the lower end of which terminates in an arcuate portion 24 adapted to rest upon the table or other surface 19. This arcuate portion 24 is conformable generally to the circular or other cross-section of a holder and is slightly undersized so that it will snap into place when swung to the dotted line position shown in Fig. 4. In order to prevent the strut 23 from swinging beyond the desired point in its operative position I have provided a projecting portion 25 which abuts the band 20, thus acting as a stop.

In Fig. 6 I have illustrated a construction in which the device is applied to a pipe having a stem 26 and a bowl portion 26' which it is desired to elevate above the table, 27 or at least support the same thereon against

falling and the pipe may, therefore, be broadly considered as the article to be supported. In this instance, instead of providing a band which encompasses a portion of the article, the parallel supporting arms 28 are directly connected to the bowl of the pipe as by pivot pins 28^a imbedded or otherwise secured therein. The arms 28 terminate in a foot portion 29 which is arranged at substantially a right angle thereto and is curved to conform to a portion of the pipe which it contacts when swung to the dotted line position shown in Fig. 6.

In Fig. 7 a pipe construction is shown in which there is a bowl 30 around which I have placed a band 31, of such size that it may be slipped over the small upper end and pressed downwardly until the frictional engagement is such as firmly to hold it in place and to this band 31 I have pivotally secured a supporting strut 32 comprising parallel arms which terminate in a curved foot portion 33 arranged at substantially a right angle thereto, the function of which is likewise to support the pipe suitably from the table or other surface 34.

In Fig. 8 I have illustrated the foot portion of the supporting construction shown in Fig. 5 as being composed of two curved or arcuate portions 35 and 36 which are hinged at a point 37. They may thus be swung to the full line position shown in Fig. 8 when the support is in its inoperative position, i. e. embracing the pipe, cigarette held or other article and stretched open to the dotted line position when in contact with the table or other supporting surface in order to give a larger spread and form a more stable support. This construction furnishes a very nice appearing one when closed and yet is of considerable size when opened or spread apart.

The many advantageous features of my invention will now be understood by those skilled in the art to which this appertains.

I claim:

In combination with a smoker's article having a tobacco receiving portion and a stem, a supporting device therefor comprising two parallel arms pivotally connected at one end to said tobacco receiving portion and a curved member connecting the other ends of said arms together, said curved connecting member being arranged in a plane at a right angle thereto and when in its inoperative position embracing a part of said tobacco receiving portion and when in its operative position providing a base for the supporting device.

In testimony whereof, I have hereunto set my hand, this 25th day of November, 1923.

ROBERT L. FARGO.
